ROTATABLE CLOSET FOR COATS OR THE LIKE

Julian von der Lancken, White Plains, N.Y., assignor to Lehigh Furniture Corp., New York, N.Y., a corporation of New York

Application October 1, 1956, Serial No. 43,147

Term of patent 14 years

(Cl. D33—8)

Fig. 1 is a perspective view of a rotatable closet for coats or the like showing my new design, the casing top and bottom, not shown, being substantially plain;

Fig. 2 is a view similar to that of Fig. 1, but with the casing rotated 180° from the position shown in Fig. 1; and

Fig. 3 is an elevational view of the rotatable closet of Figs. 1 and 2, but with the casing being partly broken away to show the interior thereof.

I claim:

The ornamental design for a rotatable closet for coats or the like, substantially as shown and described.
